US0D1095589S

(12) **United States Design Patent** (10) Patent No.: **US D1,095,589 S**
(45) Date of Patent: ** Sep. 30, 2025

(54) **DISPLAY SCREEN WITH GRAPHICAL USER INTERFACE FOR A BUILDING CONTROLLER**

(71) Applicant: **Honeywell International Inc.**, Charlotte, NC (US)

(72) Inventors: **Zhiguo Di**, Shanghai (CN); **Yidan Zhao**, Shanghai (CN); **Ji Zhang**, Shanghai (CN)

(73) Assignee: **HONEYWELL INTERNATIONAL INC.**, Charlotte, NC (US)

(**) Term: **15 Years**

(21) Appl. No.: **29/913,978**

(22) Filed: **Oct. 11, 2023**

Related U.S. Application Data

(62) Division of application No. 29/716,911, filed on Dec. 12, 2019, now Pat. No. Des. 1,006,044.

(51) **LOC (15) Cl.** **14-04**

(52) **U.S. Cl.**

USPC **D14/486**

(58) **Field of Classification Search**

USPC D14/485-495

CPC G06F 3/048-04897

See application file for complete search history.

(57) **CLAIM**

The ornamental design for a display screen with graphical user interface for a building controller as shown and described.

DESCRIPTION

The FIGURE shows a display screen with graphical user interface for a building controller.

The two outermost broken lines illustrate a building controller housing a display screen. The remaining broken lines illustrate portions of the graphical user interface. None of the broken lines form part of the claimed design.

1 Claim, 1 Drawing Sheet
